SHUTTER

George B. Richmond, Memphis, Tenn., assignor
to Hunter Fan and Ventilating Company, Inc.,
Memphis, Tenn., a corporation of New York

Application October 30, 1946, Serial No. 706,731

12 Claims. (Cl. 98—116)

1

This invention relates to improvements in shutters that are used with exhaust fans. More particularly, this invention relates to improvements in horizontally disposed shutters which are used with certain kinds of exhaust fans that are to be operated in the attics of houses or buildings and are, because of their location, commonly called attic fans.

It is, therefore, an object of the present invention to provide an improved horizontally-disposed shutter that can be used with attic fans.

Attic exhaust fans, to be of value in properly ventilating a house or building, must have comparatively large ceiling intake openings; those openings must be provided with closures to prevent excessive loss of heat from the house or building during the winter season. The two closures that are most commonly used in connection with attic fans are (1) trapdoors that are opened in the spring of the year and are closed in the fall, and (2) self-operating ceiling shutters that will open to permit escape of air during the "on" periods of the fans and will automatically close to prevent entrance of dust, heat or other objectionable matter into the living spaces of the house or building when the fans are "off." The trapdoors are workable in that they provide large, unimpeded openings through which air can be moved with little resistance, but they are undesirable since they are usually open all season and permit the undesired entry of dirt and heat into the living spaces of the house or building. As a result, the use of trapdoors with attic fans is not completely satisfactory. The self-operating shutters obviate some of the difficulties experienced with the trapdoors, because those shutters will tend to close whenever the fans are "off." However, in view of the fact that the draft of air produced by the fan is the motive force to open the shutter and in view of the fact that such a draft can exert only limited pressure, a delicate counterbalancing mechanism is necessary with the self-operating shutters to prevent serious reduction in the amount of air that can pass through those shutters. Springs or weights usually provide the necessary counter-tension in the counterbalancing mechanism to offset the weight of the shutter blades and the springs or weights also permit some adjustment to be made to meet changing operating conditions. While the automatic ceiling shutters are more desirable than the trap doors as closures for attic fans, they are themselves objectionable because (1) the counterbalancing devices can be prevented from operating properly by gradual accumulations of grease

2

or dirt on the moving parts thereof and the devices can thus prevent normal opening or closing of the shutter blades; (2) fires occurring in the house or building could create air disturbances which might act upon the shutter and cause it to open, thus permitting smoke or flames to spread to other parts of the structure, (3) the tendency of the shutter blades to close can create sufficient back pressure to noticeably reduce the air capacity of newly installed attic fans, and that tendency can become more pronounced as the fan gets dirty with the passage of time; and (4) the shutter blades are not held positively in closed position and thus back drafts in the attic can cause the shutter blades to flutter and make disturbing noises when the fan is "off."

For these various reasons, the closures that are commonly used in connection with attic exhaust fans are objectionable. The present invention obviates these objections by providing a manually-operated, horizontally-disposed ceiling shutter that is held open by a control chain and is positively closed by a compression spring whenever the control chain is released. Moreover, the shutter of the present invention embodies dependable, automatic fire protection features that operate to close the shutters and stop the fan whenever a flame or a mass of hot air reaches the proximity of the shutter. In addition, the shutter of the present invention has a strong, horizontally-disposed frame that supports the shutter blades and also supports a control bracket which is in the center of the frame and permits the shutter blades to assume uniform angular inclinations relative to the axis of the fan. Moreover, the shutter of the present invention and its operating mechanism is protected against injury due to accidental contact with obstructions in the house or building and the operating mechanism positively biases all of the shutters to closed position. It is, therefore, an object of the present invention to provide a plurality of shutter blades for an attic exhaust fan and an operating mechanism that permits the shutter blades to assume almost perpendicular inclinations when the fan is operating and to positively close each of the shutter blades when the fan is not operating.

In the shutter of the present invention, a bracket is provided that supports a collar which can reciprocate relative to the bracket and cause the shutter blades to open and close. The shutter of the present invention also provides a mercury switch which tilts into and out of circuit-breaking position in response to the movement of

the reciprocable collar. Moreover, the shutter of the present invention provides a compression spring that always urges the reciprocable collar into shutter-closing and circuit-opening position. With such a construction, it is impossible to shut off the fan motor and leave the shutter blades open or to close the shutter blades and leave the fan motor running, because the actuation of the shutter blades and the fan motor are simultaneous and are positively related together. In 10 addition, the reciprocable collar of the present invention is held in shutter-opening and circuit-making position by a chain which has a thermally-responsive link that will melt at temperatures in the neighborhood of one hundred and thirty-five (135) degrees Fahrenheit. Whenever the link melts, the collar moves to close the shutter blades and shut off the fan motor. Such a link acts promptly to obviate the creation of a chimney effect through the shutter to the attic of 20 the house or building because the very instant that the flame or hot air from a fire strikes the thermally-responsive link, it will cause that link to melt, thus permitting the reciprocable collar to move into shutter-closing and circuit-opening position under the influence of the compression spring. Such a construction provides protection of the highest type and also makes possible the ready replacement of the link. It is, therefore, an object of the present invention to provide a shutter with an upstanding bracket that carries a reciprocable collar which is biased to shutter-closing and circuit-opening position by a helical spring and is held out of shutter-closing and circuit-opening position by a chain that contains a fusible link.

The shutter of the present invention is protected against overloading of the fan motor or overheating of the wires to that motor. Such protection is inherent in the construction that coordinates the actuation of the switch with the movement of the shutter blades in such a way that the fan cannot be energized when the shutter blades are closed. As a result, it is impossible for the fan to run without having an adequate supply of air accessible to it through the open shutter, and thus the fan motor and the wires leading to that motor cannot become overheated. It is, therefore, an object of the present invention to provide a horizontally-disposed shutter that is adjacent a fan and is so connected to the motor that the shutter is always open when the motor is running.

The shutter of the present invention additionally protects the wiring of the motor by providing a channel that underlies and at least partially surrounds those wires. As a result, if flames or hot air strike the shutter, the wires of the motor will be protected from a direct blast of heat; thus the insulation on the wires will not burn or melt and permit the wires to contact each other and keep the fan running after the shutter blades have closed in response to the melting of the thermally-responsive link. It is, therefore, an object of the present invention to provide a 65 shutter with channels that underlie and partially surround the wires to the fan motor.

The shutter blades of the present invention are always held against fluttering, and thus they are practically noiseless in their operation. The fluttering is prevented when the shutter blades are in closed position by the action of a spring that urges the edges of the shutter blades against adjacent shutter blades; the fluttering is prevented when the shutter blades are in open position by 75

the action of the spring in urging the shutter blades toward closed position while a chain holds them in open position, thus hampering any movement of the shutter blades. It is, therefore, an object of the present invention to provide a spring for a shutter that prevents fluttering of the shutter blades in open and closed positions.

Other objects and advantages of the present invention should become apparent from an examination of the drawing and accompanying description.

In the drawing and accompanying description, a preferred embodiment of the invention is shown and described but it is to be understood that the drawing and accompanying description are for the purposes of illustration only and do not limit the invention and that the invention will be defined by the appended claims.

In the drawing,

Fig. 1 is a side elevational view of a portion of a shutter embodying the principles and teachings of the present invention, and it shows the shutter blades of that shutter in closed position.

Fig. 2 is a side elevational view of the shutter of Fig. 1, showing the shutter blades of the shutter in open position and also showing the socket at the opposite end of the frame.

Fig. 3 is a plan view of the portion of the shutter shown in Fig. 1 and it shows the shutter blades of the shutter in closed position, and

Fig. 4 is a partial cross-sectional view of the control device for the shutters shown in Figs. 1, 2 and 3.

Referring to the drawing in detail, the numeral 10 denotes the four L-shaped angles which form the frame for a horizontally-disposed shutter. The angles 10 have the edges thereof cut and faced together to enable the angles 10 to form a rectangle. Also forming part of the frame are two longitudinally-extending channels 11 that are joined to the sides and body of the frame and extend toward the center of the frame. The angles 10 at the sides of the frame carry L-shaped angles 13, and the angles 13 rotatably support transversely-extending pivot rods 12. The angles 10 also carry transversely-extending arms 15 that extend inwardly toward the middle of the frame and terminate in a generally square supporting plate 16. The supporting plate 16 underlies and is secured to the inner ends of the channels 11. A transversely-extending reinforcing arm 18 is positioned above each of the arms 15 and the arms 18 extend between and are attached to the supporting plate 16 and the angles 10 at the sides of the frame. The pivot rods 12 extend through the vertically-disposed walls of the channels 11 but they are rotatable relative to those walls. The frame may be secured to a house or other building in any suitable manner; it is shown as being encased in a wooden support 20 that can be nailed or bolted to the beams or joists of the house or building. The support 20 may be provided with an ornamental trim 22, and this trim can be made to blend in with the general decorative effect of the house or building.

Fixedly secured to the pivot rods 12 for joint rotation with those rods are shutter blades 24, each of which has an arcuate portion 26 at one end thereof and has a generally cylindrical portion 27 at the other end thereof. The cylindrical portions 27 are dimensioned to fit snugly over the pivot rods 12 and confine one edge of each of the shutter blades 24 for rotation relative to the frame, while permitting the other edges 70 of the shutter blades 24 to remain free. Posi-

tioned within the arcuate portions 26 of the shutter blades 24 are generally arcuate inserts 28 of moisture-resistant, resilient material which will bear against the cylindrical portions 27 of adjacent shutter blades 24 and will cooperate with the portions 27 to keep dust, air and moisture from filtering by the shutter blades 24 when those blades are in the closed position, as shown in Fig. 1. In addition, the inserts 28 will avoid metal-to-metal contact between the adjacent shutter blades 24 and will thus eliminate noise in the operation of the shutter. The four shutter blades 24 that are immediately adjacent the central supporting plate 16 are not provided with parallel extending sides, as are the rest of the shutter blades 24. Instead, those four shutter blades 24 have generally trapezoidal configurations that enable them to bear against and overlie the supporting plate 16. With those four shutter blades 24, the free edges do not overlie the cylindrical portions of adjacent shutter blades 24 but overlie the sides of the arms 15 and the sides of the supporting plate 16. In this way, the shutter blades 24 provide a substantially airtight surface for the frame when they are closed.

It will be noted that with the shutter shown in the drawing, there are four distinct groups of shutter blades 24; two groups in the right hand half of the frame and two groups in the left hand half of the frame. The two groups in each half are separated by the channels 11 and thus a separate group of shutter blades 24 is provided in each of the four quadrants of the frame. Each of the shutter blades 24, with the exception of the four shutter blades immediately adjacent the central supporting plate 16 of the frame, is provided with a hinge member 29 that extends upwardly adjacent the sides of the channels 11 that are disposed longitudinally of the frame. The hinge members 29 are rotatably attached to connecting rods 30 which extend between and connect together the hinge members 29 of any one particular group of shutter blades 24, thus permitting all of the shutter blades in that particular group to move together at the same time. The four shutter blades 24 which are most closely adjacent to the central supporting plate 16 are equipped with upstanding hinge members 31; the four shutters that are immediately adjacent the four shutters at the center of the frame are also provided with upstanding hinge members 31. The hinge members 31 are connected together for conjoint movement by the connecting rods 32. It will be noted that the four shutter blades 24 which are adjacent the four innermost shutter blades 24 have hinge members 29 as well as the hinge members 31; as a result, those particular shutter blades will move in response to the movement of the connecting rod 30 and will cause a concomitant conjoint movement of the four innermost shutter blades 24 by reason of the connecting rods 32. As a result of this construction, all of the shutter blades 24 can open and close at the same time. It should be noted that all the shutter blades 24 open with their free edges toward the center of the frame, thus providing uniform, turbulence-free flow of air past the shutter blades 24.

Levers 33 are connected to the hinge members 29 of the four shutter blades 24 which are adjacent the four innermost shutter blades 24, and those levers are connected to the ends of the crank levers 34. The crank levers 34 in turn are rotatably secured to the channels 11. Connected to points intermediate the lengths of the crank levers 34 are connecting rods 35 which extend

longitudinally of the frame and terminate adjacent the central supporting plate 16 of the frame. With this construction, movement of the connecting rods 35 away from the center of the frame causes simultaneous opening of the shutter blades 24 while movement of the rods 35 toward the center causes simultaneous closing of the shutter blades 24.

Adjacent the inwardly extending ends of the connecting rods 35 is the central supporting plate 16; projecting upwardly from the center supporting plate 16 is a hollow cylinder 36 that constitutes a center bracket for the frame. The center bracket 36 has a vertically-extending slot 38 in the opposite walls thereof, and the two slots 38 are in register with each other. The exterior surface of the bracket 36 is smooth; it permits uninterrupted reciprocation therealong of a collar 42 which has an inner diameter substantially the same as the outer diameter of the bracket 36. The collar 42 has a transversely-extending opening therethrough, and that opening carries the pin 44 which passes through and registers with the slot 38 in the bracket 36. The pin 44 limits the upward movement of the collar 42 and it may, if desired, also serve to limit the downward movement of the collar 42. Secured to the central supporting plate 16, but spaced horizontally therefrom, is a vertically-disposed support 46 and that support carries a V-shaped rocker arm 48 which can oscillate relative to the support 46. The vertical support 46 is so positioned relative to the bracket 36 that the rocker arm 48 registers with and engages the pin 44 of the collar 42 and the rocker arm 48 is set so the pin 44 bears against the inner surfaces of the V of the rocker arm 48. A mercury switch 50 is secured to and rotates with the rocker arm 48, and the mercury switch 50 is connected by means of conductors 49 to a socket 47. The socket 47 receives the insulated conductors 53 from an alternating current source, not shown, and the socket 47 also receives the insulated conductors 51 that pass to the fan motor, not shown. The plug 47 is so wired that one of the leads from the alternating current source passes directly into the insulated cord 51 while the other conductor from the insulated cord 53 is connected through the switch 50 to the other lead of the cord 51. Thus when the mercury switch 50 is in one position, the fan motor will be energized, and when the mercury switch 50 is in its other position, the fan motor will not be energized. As shown in the drawing, the mercury switch 50 will cause the motor to be energized when the shutters are open, as they are in Fig. 2 and it will cause the motor to be de-energized when the shutters are closed, as they are in Figs. 1 and 3. The motor and fan are secured to a supporting frame, not shown, and that supporting frame will rest on the section 57 of rubber hose that is secured to the support 20. This section 57 will absorb vibration and noise and will make the installation more efficient and desirable.

The collar 42 is provided with a horizontally projecting flange 43 and the flange 43 is rotatably secured to the levers 52. The levers 52 are in turn rotatably secured by the pivot 53 to the inwardly extending ends of the connecting rods 35 and to the hinged levers 54 that are rotatably attached to the plate 16. With such a construction, the reciprocation of the collar 42 will cause a knee action of the levers 52 and 54 that will cause a reciprocation of the connecting rods 35 and as previously indicated, this recipro-

cating action of the connecting rods 35 will cause rotation of crank arm 34 and a concomitant opening and closing of the shutter blades 24. The movement of the collar 42 is regulated by the conjoint action of the spring 55 that encircles the bracket 36 and presses against the underside of the collar 42, and a chain 58 which acts upon the pin 44 through the medium of a thermally responsive link 56. The spring 55 urges the collar 42 and the switch 50 into closed shutter and open circuit position and to start the fan motor and to open the shutter blades 24, it is necessary to pull the chain 58 downwardly and to maintain that chain in a downwardly position.

This requires maintaining the thermally-responsive link 56 intact. The link 56 will remain intact during all normal operating temperatures of the shutter but in the event of a fire occurring in the house or other building structure in which the shutter is installed, the flame or hot air that reaches the shutter will instantaneously melt the fusible link 56, since the link melts at temperatures around one hundred and thirty-five (135) degrees Fahrenheit. Immediately upon such melting, the collar 42 will be released and will move upwardly, breaking the circuit in the mercury switch 50, forcing the shutter blades 24 closed, and holding them closed. This will eliminate any chimney effect through the shutter. The chain 58 has a convenient loop 60 at the bottom thereof to permit easy manipulation of the chain and the chain 58 is held in the shutter-opening and circuit-making position by slipping it into a slot 62 that is contiguous with an opening, not shown, in the bottom of the bracket 36. That opening has a diameter that approximates the interior diameter of the bracket 36, and the slot is V-shaped with the open end of the V forming part of the opening. With such a slot, it is possible to hold the chain merely by moving the chain into the position shown in Fig. 4 where one of the round sections of the chain 58 will fit into the slot 62 and will be held there by the pressures exerted by the spring 55. Mere movement of the chain 58 into the center of the large opening with which the slot 62 is contiguous will permit the chain to move upwardly into circuit-opening and shutter-closing position.

It will be noted that this construction provides a single point of application of force for both the shutter-opening mechanism and the mercury switch, namely, the pin 44. This is a very important feature because it eliminates the necessity of precisely dimensioning a chain that will simultaneously act upon a switch and the shutter-operating mechanism. Moreover, it eliminates the possibility that one portion of the chain may break and permit the fan to operate while the shutter blades are closed; in addition, it facilitates the use of a single fusible element in controlling the movement of the shutter blades and the actuation of the switch. With the construction of the present invention, it is possible to use a chain of almost any suitable length in operating the shutter, and there is no problem of precisely dimensioning that chain.

It should also be noted that the construction of the present invention permits the chain to hang down in the direction of movement of the collar 42. As a result, the chain does not have to be passed around pulleys, with consequent increases in friction and consequent increases in the stresses in the chain. Moreover, it facilitates locking of the chain in position by per-

mitting of one of the sections of the chain 58 into the slot 62.

The construction shown in the drawing is also highly desirable because it has the center bracket, connecting rods, and operating levers thereof spaced inwardly from the edges of the frame; thus those elements are out of the way of beams, joists and other structural elements of the house or building in which the shutter is used. As a result, the shutter can be fitted into places where other shutters cannot be set and the operating of the shutter will not injure or be injured by structural elements of the house or structure. Moreover, it will be noted that the bracket 36 is hollow and is not closed at the top or bottom; thus the thermally-responsive link 56 is directly in the path of flame or hot air evolved by a fire and will respond promptly to serious increases in temperature in the vicinity of the shutter. Moreover, it will be noted that the free edges of the shutter blades 24 are definitely held against the pivoted edges of adjacent shutter blades 24 and the resilient sealing inserts 28 will keep out dust, dirt, rain and other objectionable materials. Furthermore, it will be noted that the spring pressure is distributed over each of the shutter blades 24, and thus no single shutter blade has to absorb a large pressure.

In addition, the construction of the present invention permits the wires 49 to lie under the various operating levers and thus keeps them out of the way of the shutter blades 24. The construction additionally protects the wires 49 by reason of the longitudinally-extending channels 11 which underlie and partially surround those wires. Thus hot blasts of air or flames cannot directly contact the wires and cannot burn off or melt the insulation of those wires. It will also be noted that whenever the collar 42 moves, and that collar will move at all times it is not positively held in shutter-opening and circuit-making position, the mercury switch 50 will be moved to circuit-opening position. The use of the mercury switch 50 is highly advantageous because it is able to provide long life and quick circuit-opening without arcing; in addition, in the event of fire, there is but little possibility that the flame could contact the mercury switch 50 since the bracket 36 is spaced to one side of the mercury switch 50 and the mercury switch is shielded from the open slot 38 by the rocker arm 48.

Whereas a preferred embodiment of the present invention is shown and described in the drawing and accompanying description, it is obvious to those skilled in the art that various changes may be made in the form of the invention without affecting the scope thereof.

What I claim is:

1. The combination of a frame, a plurality of shutter blades rotatably secured to said frame, a switch movable into "on" and "off" position, a lever pivoted to said frame, a rod extending between the free end of said lever and one of said shutter blades, a second rod connecting the free ends of said shutter blades together, a reciprocable actuator, a connecting rod extending from said actuator to a point on said lever which is intermediate the ends of said lever, whereby a small movement of said actuator provides a large movement of said shutter blades, a link between said shutter blades and said switch whereby movement of said shutter blades is accompanied by movement of said switch, resilient means biasing said actuator to shutter-closing position, and

manually operable means adapted to move said actuator, said resilient means preventing fluttering of said shutter blades in open or closed position and closing the shutter and opening the circuit whenever the manually operable means is released.

2. The combination of a frame, a plurality of shutter blades rotatably secured to said frame, and means to move said shutter blades, said means including a connecting rod pivotally secured to said shutter blades whereby said shutter blades move in unison, a crank lever pivotally secured to said frame, an intermediate link secured to said crank lever and to said connecting rod, a reciprocable member, a knee action linkage connected to and actuatable by said reciprocable member, a lever that is connected to said crank lever and to said knee action linkage and causes movement of said shutter blades whenever said reciprocable member reciprocates, a switch movable into "on" and "off" position, a projection movable with said reciprocable element to actuate said switch, and resilient means biasing said reciprocable member to circuit-breaking and shutter-closing position, said reciprocable member serving as a single point of application to which a single force can be applied to cause simultaneous movement of the shutter blades and actuation of the switch.

3. The combination of shutter blades and an actuating mechanism therefor that comprises a frame, a plurality of shutter blades rotatably secured to said frame, a stationary bracket secured to and carried by said frame, a collar movable relative to said stationary bracket, a spring biasing said collar for movement toward one end of said stationary bracket, a switch responsive to the position of said collar to move to "on" or "off" position, manually operable means to determine the position of said collar relative to said bracket, and connecting links between said collar and said shutter blades to control the opening or closing of said shutter blades, said bracket being disposed centrally of said frame, said bracket being hollow and having both ends open whereby flames can pass directly through said bracket and contact a fusible link which is positioned within and movable relative to said bracket and is part of said manually operable means.

4. In a shutter, a frame, a central supporting plate, secured to said frame, a plurality of shutter blades spaced outwardly from said supporting plate, a hollow cylinder secured to and projecting upwardly from said plate with its axis normal to said plate, a slot in the wall of said cylinder that is parallel to the axis of said cylinder, a collar that telescopes over said cylinder and is reciprocable relative to said cylinder, a pin that is carried by said collar and extends through said slot into said cylinder, a fusible link connectible to said pin, a plurality of levers positioned between said collar and said shutter blades that open and close said shutter blades in response to movement of said collar, resilient means biasing said collar for movement to shutter-closing position, and a manually operable element connected to said fusible link and thus to said collar, said manually operable element being movable to move said collar to shutter-opening position.

5. In a shutter, a frame, a central supporting plate secured to said frame, a plurality of shutter blades spaced outwardly from said supporting

plate, a hollow cylinder secured to and projecting upwardly from said plate, a slot in the wall of said cylinder that is parallel to the axis of said cylinder, a collar that telescopes over said cylinder and is reciprocable relative to said cylinder, a pin that is carried by said collar and extends through said slot into said cylinder, a fusible link connectible to said pin, a chain connectible to said fusible link, a plurality of levers between said collar and said shutter blades that open and close said shutter blades in response to movement of said collar, resilient means biasing said collar for movement to shutter-closing position, a rocker arm rotatably positioned adjacent said cylinder, and a mercury switch carried by said rocker arm and movable to "on" and "off" position, said rocker arm being operable by said pin carried by said collar.

6. In a shutter, a frame, a central supporting plate secured to said frame, a plurality of shutter blades spaced outwardly from said supporting plate, a hollow cylinder secured to and projecting upwardly from said plate, a slot in the wall of said cylinder which is parallel to the axis of said cylinder, a collar that telescopes over and is reciprocable relative to said cylinder, a pin that is carried by said collar and extends through said slot into said cylinder, a fusible link connectible to said pin, a chain connectible to said fusible link, a plurality of levers positioned between said collar and said shutter blades that open and close said shutter blades in response to movement of said collar, resilient means biasing said collar for movement to shutter-closing position, a rocker arm rotatably positioned adjacent said cylinder, a mercury switch carried by said rocker arm and movable to "on" position and "off" position, said rocker arm being operable by said pin carried by said collar, and a switch that is adjacent to said collar and is responsive to movement of said collar to energize and de-energize a motor which actuates a fan adjacent to said shutter, said resilient means also biasing said collar for movement to cause said switch to de-energize said motor.

7. The combination of a frame, a support disposed inwardly of said frame, said support being smaller than said frame and being adjacent the center of said frame, a channel which is secured to said frame and to said support and spanning the distance between said frame and said support, a plurality of pivots having their inner ends secured to said channel and having their outer ends secured to said frame, a plurality of shutter blades that are supported by said pivots, a switch that is mounted on said support and is movable into "on" and "off" position, a manually operable reciprocating element confined for reciprocating movement between "on" and "off" position, a linkage that extends between said manually operable reciprocating element and said shutters to cause movement of said shutter blades, a second linkage extending between said manually operable reciprocating element and said switch, and leads extending to said switch, said channel having upwardly extending sides that form a protection and cover for said leads, said switch being carried by said support and being located inwardly of said frame, said leads overlying and being protected by said channel whereby blasts of flame or hot air cannot directly contact said leads.

8. The combination of a frame, a plurality of shutter blades rotatably secured to said frame by pivots, and means to move said shutter blades,

11

said means including eccentric hinge members which are secured to said shutter blades at points spaced from said pivots and which project outwardly from said shutter blades, a connecting rod pivotally secured to said eccentric hinge members, a link pivotally secured to one end of said connecting rod, a crank lever pivotally secured to said link and to said frame, a support secured to said frame, a reciprocable member guided for reciprocable movement by said support, a linkage comprising a plurality of links pivoted together at one end thereof, the free end of one of said links being pivoted to said frame, the free end of the other of said links being pivoted to said reciprocable member, a pivot pivotally connecting together said links of said linkage, resilient means disposed between said reciprocable member and said frame, said linkage being actuatable by said resilient means whenever said reciprocable member moves to move said pivot transversely of the direction of reciprocation of said reciprocable member, a lever connected to said crank lever intermediate the ends of said crank lever and is linked to said reciprocable member by said pivot and said linkage, a projection mounted on said reciprocable member, said projection being movable through a predetermined path when said reciprocable member moves, a switch that is adjacent the path of movement of said projection and that is movable into "on" or "off" position by said projection whereby actuation of said switch is controlled by reciprocation of said reciprocable member and the concomitant movement of said projection, and holding means secured to said reciprocable member, said holding means being selectively and releasably engageable with said frame, said resilient means biasing said reciprocable member to circuit-breaking and shutter-closing position.

9. In a shutter that is disposed adjacent a fan and has a frame, a plurality of shutters rotatably secured to said frame by pivots, a connecting rod secured to said shutters to cause conjoint movement thereof, and a manually operated actuator, the improvement which comprises a lever having one end thereof pivoted to said frame adjacent said pivots, a link extending between the free end of said lever and said connecting rod, said link responding to rotation of said lever about said frame to move said connecting rod and thus move said shutters, and a driving rod that is connected to said actuator and to a pivot intermediate the ends of said lever, said driving rod being movable to cause movement of said lever, the securing of said driving rod to a pivot intermediate the ends of said lever and the securing of said link to the free end of said lever causing said free end of said link to move farther than said driving rod moves.

10. A shutter that comprises a frame, a plurality of shutter blades secured to said frame by pivots, a lever pivotally secured to said frame adjacent said pivots, a connecting link extending between said shutter blades and a point on said lever, said point on said lever being spaced from the point where said lever is pivotally secured to said frame whereby said connecting link and said shutter blades will move whenever said lever moves, a rod pivotally secured to said lever intermediate said points on said lever, and a movable element connected to said rod and is

10

movable to cause movement of said rod to move said lever and thereby cause opening or closing of said shutter blades, the securing of said rod to said lever intermediate said points on said lever enabling a predetermined movement of said rod to cause a movement of the first said point on said lever and a movement of said shutter blades which are greater than the movement of said movable element and said rod.

11

11. A shutter that comprises a frame, a plurality of shutter blades that are rotatably secured to said frame, and means to provide movement of said shutter blades, said means including a reciprocable member, a lever that has one end pivoted to said frame and has the other end free, a tie rod connected at one end to said lever and connected at the other end to one of said shutter blades, a link that engages said shutter blades and connects them for movement in unison, a knee action linkage which includes a plurality of levers that are connected together and that are actuatable by said reciprocable member to move transversely of the direction of reciprocation of said reciprocable element, and a connecting rod pivotally secured to said lever and to said knee action linkage, said connecting rod being secured to said lever at a point intermediate the ends of said lever and intermediate the pivoted connection between said lever and said frame and the connection between said lever and said tie rod, said reciprocable member being movable to actuate said knee action linkage and thus move said connecting rod, thus causing rotation of said lever, movement of said tie rod, rotation of said one shutter blade, movement of said link, and rotation of said other shutter blades, the securing of said connecting rod intermediate the ends of said lever and intermediate the pivoted connection between said lever and said frame and the connection between said lever and said tie rod providing a multiplication of movement for said shutter blades.

12

12. In a shutter that is disposed adjacent a fan and has a frame, a plurality of shutters rotatably secured to said frame by pivots, a connecting rod secured to said shutters to cause conjoint movement thereof, and a manually operated actuator which has a path of movement of predetermined length, the improvement which comprises a hollow support for said actuator, said support being supported by said frame and providing a path for air from one side of said frame to the other, a fusible link movably positioned within said hollow support and held in said path for air, said link normally being connected to said actuator and normally being movable to move said actuator, said link normally being movable concomitantly with said actuator through a path of movement that is equal to the path of movement of said actuator but is within said hollow support, said hollow support having a length greater than said paths of movement and being in registry with the path of movement of said fusible link, and a flexible chain connected to said actuator by said fusible link, the lower end of said hollow support being open to said one side of said frame to permit flames or hot air to contact and act upon said fusible link, said support protecting said fusible link against breakage through contact with other elements of said shutter, said link being fusible to permit movement of said actuator independently of said chain.
